CLAIM

The ornamental design for a 35 mm camera, as shown and described.

DESCRIPTION

FIG. 1 is a front, top and left side perspective view of a 35 mm camera of our new design;

FIG. 2 is a rear elevational view thereof;

FIG. 3 is a top plan view thereof;

FIG. 4 is a bottom plan view thereof;

FIG. 5 is a left side elevational view thereof;

FIG. 6 is a right side elevational view thereof;

FIG. 7 is a front, top and left side perspective view thereof, with the lens cover in an open position and with the lens in a retracted position; and

FIG. 8 is a front, top and left side perspective view thereof, with the lens cover in an open position and with the lens in a projected position.

*FIG. 1**FIG. 2**FIG. 3**FIG. 4**FIG. 5**FIG. 6**FIG. 7**FIG. 8*
